UNITED STATES PATENT OFFICE.

GEORGE C. HARRIS, OF PEABODY, AND WILLIAM F. MUFF, OF NEWTON, KANSAS.

BALLAST-SCREENING MACHINE.

1,214,674.

Specification of Letters Patent. Patented Feb. 6, 1917.

Application filed April 24, 1916. Serial No. 93,205.

To all whom it may concern:

Be it known that we, GEORGE C. HARRIS and WILLIAM F. MUFF, citizens of the United States, residing at Peabody and 5 Newton, respectively, in the counties of Marion and Harvey and State of Kansas, have invented certain new and useful Improvements in Ballast-Screening Machines, of which the following is a specification, 10 reference being had to the accompanying drawings.

This invention is a ballast screening machine.

The usual method of screening and placing 15 the ballast in a road-bed, such as that of a railroad, is by hand. This method is costly and consumes considerable time. In the hand method, a screen box is set up in a slanting position somewhere on the right 20 of way, the gravel to be screened is brought to the box, thrown against the meshes of the screen, thus causing the dirt and refuse to fall through. The gravel is then shoveled up, put into wheelbarrows and transported 25 to the various points, where it is desired to place it. This requires much manual labor and is very slow and inefficient, as not many cubic yards of gravel can be screened in one day. This makes for a high labor cost.

30 This invention aims to overcome the above objections found in existing methods and has for an object to provide an easily transportable machine for cleaning and depositing ballast.

35 A further object of the invention is to provide a ballast screening machine which is adapted to be mounted upon a hand car and readily demounted therefrom so that the hand car may be removed from the track 40 to permit the passage of a train, the machine being so light that it may be quickly removed from the hand car or readily replaced thereon, the power to operate the machine being taken from the motor used 45 for operating the hand car.

Another object is to provide a machine wherein the refuse is separated from the ballast and deposited away from the road-bed.

50 A still further object is to provide a machine which will require little power for operation, not liable to derangement comprising a minimum of parts and depositing the materials with a low labor cost.

55 Another aim is to provide a machine in which the operations of conveying screen-

ing and depositing the ballast and refuse are continuously and consecutively done.

A purpose of the invention is to provide a machine that may be readily attached or 60 detached from a road repair car and when attached, may be quickly connected to the motive power operating the repair car.

To accomplish these various objects, the invention broadly comprises a frame, a conveyer and a chute or trough, a deflector, a screen, an apron for the refuse material, a conveyer, driving elements for the several conveyers and the screen, and means to connect the driving elements with a suitable 70 source of power.

A practical form of invention is disclosed in the accompanying drawings, in which—

Figure 1 is a side elevation; Fig. 2 is a perspective view; Fig. 3 is an end elevation 75 of the screen end; Fig. 4 is an elevation of the conveyer end.

As shown in Fig. 1, there is a framework provided for supporting the various elements in their operative positions with 80 reference to each other. This framework consists of a plurality of bottom sills 5. This provides a foundation to which the stanchions 6, 7 and 8 are connected at their lower ends. These stanchions may be connected in any suitable manner. Extending outwardly from the stanchion 6 near its upper end is a top sill or chord member 9 which at its outer end is connected to the bottom sill 5. These two sills may 85 be connected in any suitable form or manner. The stanchions 7 and 8 may be secured to this top sill 9 in any preferred manner. At the outer end or juncture of the two sills 5 and 9, there is positioned an 90 adjustable pulley 10. Over this adjustable pulley 10 runs a conveyer belt 11. This conveyer belt is of the usual or customary endless type and runs over another pulley shown at 12. This pulley 12 is mounted in 100 any suitable manner, as for instance by the ordinary or common form of bearing 13. This bearing 13 may be carried by or secured to the stanchions 7. A trough or chute 14 is provided for the conveying of 105 the material by means of the conveyer belt 11. This conveyer trough may be of any preferred form, though, as disclosed in this device, it is of the usual or customary trough form having somewhat flaring sides. 110

To maintain the top sills in a spaced relation and to afford additional strength, a

brace 15 connects the two sills at a convenient point intermediate of the ends of the top sills. Connected to the top of the stanchion 6 is another sill 16. This sill 16 extends rearwardly and connects in a suitable manner with the bottom sill 5. Across the tops of the stanchions 6, there may be placed the brace 17 which will tend to make the structure more secure and stable. To this brace 17 there may be connected or suspended therefrom in any suitable manner, a bearing 18 of any preferred type. Suitably positioned upon the stanchions 6, is an idler pulley 19. Over this idler pulley runs a chain belt 20.

At the rear or screen end of the machine, are positioned two suitable supporting members 21. These supporting members are secured to the bottom sills 5 in any suitable manner. These supporting members 21 also carry bearings 22 in which revolves a shaft 23. Disposed on this shaft is a sprocket wheel 24. The chain 20 co-operates with this sprocket 24, the idler pulley 19 and a sprocket 25 carried on the shaft 26. This shaft 26, the sprocket 25 and the pulley 12 are mounted upon the stanchion 7. Also disposed on the shaft 23 is a beveled pinion 27. Co-operating with the beveled pinion 27 is a beveled gear 28 mounted on the shaft 29. This shaft 29 revolves in suitable bearings 30 which may be mounted upon a cross brace 31 which connects the supporting members 21 together. The other end of the shaft 29 is carried in the bearing 18. Secured to the shaft 29 in any suitable manner, such as is shown by the arms 32 extending outwardly, is the revolving screen 33. The revolving screen 33 is preferably disposed at an angle and revolves concentrically with the shaft 29 to which it is secured. This revolving screen may have its foraminous openings of any suitable size or shape, though in the present device it is thought preferable to make them of circular form. This revolving screen may be made of one piece of metal formed into cylindrical shape or it may be made of segments which may be attached to each other in any suitable manner and thereby form an entire screen. Positioned between the revolving screen 33 and the conveyer trough 14 is another trough or apron 34 for conveying material brought up by the conveyer belt 11 to the screen 33. This permits the gravel and dirt to be continuously fed into the revolving screen. Positioned below the revolving screen 33 is another conveyer belt 35, which will convey the refuse away from the road bed. This conveyer belt runs upon suitably mounted pulleys, one of which is indicated at 36 and another at 37. The pulley 36 is mounted on a bearing block 38 on the stanchion 6. The pulleys 37 may be mounted in a similar manner or in any other suitable way, as

shown at 42 in the bottom sill 5. Disposed underneath the conveyer belt 35 is a chute 39, preferably trough shaped, for the purpose of conveying refuse from road bed.

This machine is adapted to be mounted upon a hand car and rest upon transversely extending beams 40 fitted to the ordinary type of gasolene hand car, such as is commonly used upon railroad systems. The gasolene motor shaft may be quickly and readily attached to the shaft 26 from which the conveyer belt 11 is driven and the screen 33 revolved and the conveyer belt 35 is also driven. This makes a very compact form of machine.

By mounting the screening mechanism as above described, the machine is adapted for practical use on railroad lines inasmuch as the machine may be readily removed from the hand car itself and the hand car readily removed from the track to permit the passage of a train. If this were not the case the machine with its supporting car would have to be run off on a siding every little while to permit the passage of a train and then run back again to the place where the ballast is being screened. The waste of time consequent from this operation and the cost in wages paid to the crew of the car when the ballast screening machine is out of operation and waiting on a siding, would render the cost of screening ballast by this means excessive and practically prohibitive.

In operation, the material to be screened is thrown upon the conveyer belt 11, which travels in the trough 14 and is conveyed to the trough 34, thence to the revolving screen 33. This screen 33, by its continued rotation, screens the dirt from the gravel, the dirt and refuse dropping onto the conveyer belt 35, which deposits it on the apron 39 by means of a scraper or deflector 43. This deflector or scraper may be suitably supported so that it may be made adjustable with reference to the conveyer and to its point for deflection. One means is shown by the supporting arm 44 which is connected to the frame. This apron 39 disposes of the dirt and refuse at some distance from the road-bed. As the screen 33, mounted on the shaft 29 is preferably disposed at an angle with the sill member 5, its continued rotation causes the screened gravel to pass to its lower end, where by means of a suitable discharge chute, the trough 45 positions the gravel between the ties. Through this method, there is only one shoveling operation necessary and that is the one at the time of placing the material in the conveyer trough and upon the conveyer. In order to maintain the tension for the proper conveying of the material by the conveyer belt 11, the pulley 10 is preferably made adjustable and one form of adjusting means is shown at 41. In practice, it may be found desirable

to vary the tension in the chain belt 20 in order that the best results may be obtained from its use and, to this end, the pulley 19 may also be made adjustable.

5 The several and various parts of this machine may be made of such suitable material, as will best adapt the machine for practical use to the end that it may have sufficient strength and rigidity in all of its parts to 10 perform the various functions required of it.

Minor changes in form and details of construction may be resorted to without departing from the spirit of our invention or from the scope of the appended claims.

15 Having described our invention, what we claim is:—

1. The combination with a motor operated hand car having laterally extending supporting beams, of a ballast screening mechanism comprising a supporting frame normally resting upon the beams, a rotatable screen mounted thereon and discharging at one end of the frame, a conveyer delivering into the rear end of the screen and extending to the other end of the frame, and a conveyer extending below the whole length of the screen to receive the waste discharged from the screen, means for causing the discharge of materials from the last named conveyer laterally beyond the frame, and a unitary driving means for the screen and the conveyer operatively driven by the hand car motor.

2. A ballast screening machine comprising a supporting frame having longitudinally directed sills, a rotatable upwardly inclined screen operatively supported upon the sills and above the same and extending longitudinally of the sills, said screen discharging at one end of the frame, a conveyer extending from the opposite end of the frame to the raised end of the screen and discharging thereinto, a belt conveyer oper-

atively supported beneath the entire length of the screen, a transversely extending laterally projecting chute into which said belt conveyer discharges, a power shaft mounted on the frame, and means for driving the several conveyers and the screen from said power shaft.

3. A ballast screening machine comprising a supporting frame having longitudinally directed sills, a rotatable inclined screen mounted upon the frame above the sills and discharging at one end of the frame, a transverse shaft mounted in said last named end of the frame and operatively geared to the screen and having a sprocket wheel, a belt conveyer operatively supported upon the frame above the sill beams and extending beyond the sill beams at one end, a shaft upon which the conveyer is mounted having a sprocket wheel geared with the first named sprocket wheel, said shaft constituting a driving shaft, a chute discharging into the upper end of the screen and onto which said conveyer discharges, a belt conveyer operatively supported upon the frame above the sill beams and disposed beneath the entire length of the screen, means driven by said driving shaft operating with said belt conveyer in its upper flight moving upward and toward the upper end of the screen, and a laterally disposed chute into which said last named conveyer discharges, the chute being supported upon the frame and extending laterally beyond the frame.

In testimony whereof we hereunto affix our signatures in the presence of two witnesses.
